[57] CLAIM

The ornamental design for cable t.v. connector for marine vessel hulls or the like, as shown and described.

DESCRIPTION

FIG. 1 is a top view of a cable t.v. connector for marine vessel hulls or the like, showing my new design;

FIG. 2 is a side elevational view thereof, all sides being identical; and

FIG. 3 is a bottom plan view thereof;

FIG. 4 is a cross-sectional view taken across lines 4—4 of FIG. 3.

Fig. 1.

Fig. 2.
